UNITED STATES PATENT OFFICE.

GEORGE WATSON, OF LEEDS, ENGLAND.

FURNACE FOR THE DESTRUCTION OF TOWN REFUSE.

SPECIFICATION forming part of Letters Patent No. 713,024, dated November 4, 1902.

Original application filed April 15, 1902, Serial No. 102,976. Divided and this application filed June 18, 1902. Serial No. 112,177. (No model.)

To all whom it may concern:

Be it known that I, GEORGE WATSON, a subject of the King of Great Britain, and a resident of Lord Street Works, Whitehall road, 5 Leeds, formerly of 5 Greek street, Leeds, county of York, England, have invented certain new and useful Improvements Relating to Furnaces for the Destruction of Town Refuse, of which the following is a specification.

This invention relates to the charging opening or mouth and the lid or cover therefor in the furnace of a refuse-destructer of that type in which the refuse instead of being 15 pushed in by hand is shot directly into the furnace from the collecting-carts or from tipping-wagons, storage-bins, charging-trucks, grabs, containers, or other apparatus above the furnace.

20 The object of said invention is to render the furnace mouth and cover perfectly smoke-tight when closed, and to this end I provide them with a liquid seal; and my improvement consists in the combination of lid or cover 25 and liquid seal hereinafter described and claimed, whereby a very effective sealing is provided and great facility is afforded for operating the cover.

In the accompanying drawings, Figure 1 is 30 a longitudinal section of the charging-opening of a furnace which has my invention applied, and Fig. 2 is a transverse section of the same.

A is the charging opening or mouth of the 35 furnace, having its sides formed by or lined with a deep trough 1, which contains the water or liquid for forming the seal.

2 is the lid or cover of a size and form to 40 cover and lap over the inner edges of the lining-trough 1 and dip into the liquid therein. The trough 1 is of a depth sufficient to receive the lid or cover or the greater portion thereof, as shown in dotted outline in Fig. 1, when the latter is moved aside from the 45 furnace-mouth. The said cover is carried by

arms 3, which are radial to and fastened upon pivots 4, which have bearings in opposite sides of the furnace-mouth or lining-trough, and balance-weights 5 are applied in connection with said arms for counterbalancing the lid or cover. On one of the pivots 4 is a wheel 6, around which and around another wheel 6*, supported in fixed bearings above the furnace-mouth, there runs a chain 7 for rocking the arms 3 for moving the lid or cover 2 to and from between the position covering and closing the furnace-mouth, in which it is shown in full outline in Figs. 1 and 2, and the position (shown in dotted outline in Fig. 1) to which it is turned aside into the trough 1 for opening the furnace-mouth. The chain 7 may be operated by any suitable means—as, for example, by a worm 14, supported in bearings above the furnace-mouth and engaging with a worm-wheel 13, attached to the chain-wheel 6*.

The depth of the trough gives it a capacity which renders it available for heating water for any useful purpose—as, for example, the heating of feed-water for a steam-boiler.

It will be understood that the refuse may be fed into the charging-opening by being shot either directly from tipping carts or wagons or from grabs or containers.

What I claim as my invention is—

The combination of a cover for the charging-opening of a refuse-destructer furnace, 75 rocking arms and pivotal supports therefor carrying said cover, and a trough surrounding said opening and serving the two purposes 80 of containing the liquid for sealing the cover when closed and of receiving the cover when open, substantially as herein described.

In testimony whereof I have signed my name to this specification in the presence of 85 two subscribing witnesses.

GEORGE WATSON.
